UNITED STATES PATENT OFFICE

2,649,662

BROACH SHARPENING MACHINE

Benedict Welte, Lake Orion, Mich., assignor to
 Colonial Broach Company, Warren Township,
 Mich., a corporation of Delaware

Application November 5, 1949, Serial No. 125,705

2 Claims. (Cl. 51—50)

1

The present invention relates to improved broach sharpening machines.

It is an object of the invention to provide an improved universal broach sharpening machine adapted for the sharpening of both round and surface broaches, including separate handles, one for feeding the grinding wheel in the sharpening of round broaches wherein a relatively slight movement of the grinding wheel transversely of the broach is required, and another for feeding the grinding wheel in the sharpening of surface broaches wherein a relatively large movement of the grinding wheel transversely of the broach is required, and means selectively connecting the handles to render them operable for feeding the grinding wheel so that when one of the handles is operatively connected for feeding the grinding wheel, the other handle is disconnected and ineffective.

Another object of the invention is to provide an improved machine for sharpening broaches of the above mentioned type including a removable link means readily connectable to and disconnectable from each of the handles for readily rendering either of the handles as desired, operatively connected for feeding the grinding wheel.

It is also an object of this invention to provide an improved broach sharpening machine including an adjustable stop mechanism for limiting the infeeding of the grinding wheel in sharpening round broaches, and which mechanism may readily be adjusted by the operator from his normal operating position at the front of the machine.

A further object of this invention is to provide an improved broach sharpening machine including an adjustable stop mechanism for limiting the infeeding of the grinding wheel in the sharpening of round broaches, which permits the operator to rapidly feed the grinding wheel toward the broach until the adjustable stop is engaged, thereby speeding up the broach sharpening operation and eliminating the necessity for the operator infeeding slowly to avoid feeding of the grinding wheel beyond a desired point.

Other and more detailed objects of the invention will become apparent from a consideration of the following specification, the appended claims and the accompanying drawings, wherein:

Figure 1 is a broken perspective view of a broach sharpening machine embodying the present invention, showing the machine set up for sharpening round broaches;

Fig. 2 is a broken perspective view of the machine illustrated in Figure 1 showing the machine set up for sharpening surface broaches;

Figure 3 is a broken enlarged sectional view of the machine illustrated in Figure 1, taken along the line 3—3 thereof;

Fig. 4 is an enlarged broken plan view of the machine illustrated in Figure 1;

Fig. 5 is an enlarged sectional view of the construction illustrated in Fig. 4, taken along the line 5—5 thereof;

2

Fig. 6 is a broken enlarged sectional view of the construction illustrated in Fig. 4, taken along the line 6—6 thereof;

Fig. 7 is a broken enlarged view of the construction illustrated in Fig. 5, taken along the line 7—7 thereof;

Fig. 8 is a broken enlarged sectional view of the construction illustrated in Fig. 7, taken along the line 8—8 thereof;

Fig. 9 is an enlarged broken sectional view of the construction illustrated in Figure 1, taken along the line 9—9 thereof;

Fig. 10 is a broken sectional view of the construction illustrated in Fig. 9, taken along the line 10—10 thereof;

Fig. 11 is an end elevational view of the machine illustrated in Figure 1;

Fig. 12 is a sectional view of the construction illustrated in Fig. 11, taken along the line 12—12 thereof; and

Fig. 13 is a longitudinal sectional view of a conventional round broach.

Referring to the drawings, and particularly to Figures 1, 3, 4 and 11, the broach sharpening machine there illustrated comprises a main base 20 having a horizontally movable work slide 22 supported on ways 21 in any suitable manner. The work supporting slide 22 is adapted to support a pair of conventional centers 24 and 26 (see Fig. 1) for rotatably supporting a round broach 28. The center 24 is part of a motor driven head stock mechanism indicated generally at 30, by means of which the center 24 and the dog 32 may be rotated in order to rotate the broach during the sharpening operation. The motor driven head stock 30 and the tail stock 34 are adjustable along the slide 22 to accommodate broaches of different lengths. The slide 22 may also support a pair of steady rests 36.

The work slide 22 is moved along the ways 21 by a handwheel 23 disposed at the front of the base 20 and secured to a shaft 25 extending into a gear box 27 mounted in the base 20 and housing a suitable reduction gear train generally indicated at 29, including a spur gear 31 operatively engaging a rack 33 mounted on the work slide 22.

When the machine is to be used for sharpening flat or surface broaches, the table is provided with a suitable chuck such as the magnetic chuck 38 illustrated in Fig. 2.

The machine is provided at the rear thereof with a vertical slide 40 guided and supported in suitable ways 42 on the base 20, as best shown in Fig. 4. The vertical slide 40 is hollow and is open at its forward face, as best shown in Fig. 3, in order to permit a gear housing 44 which is fixed to the rear wall of the base 20, to project into the slide without interfering with the vertical movements of the slide.

As best shown in Fig. 3, the gear housing 44 rotatably supports a worm wheel 46 disposed with its axis extending vertically in bearings 48 and 50 which hold the worm wheel 46 against

axial movement. The housing 44 also rotatably supports a worm 52 with its axis extending horizontally and with the worm in driving engagement with the worm wheel 46. The worm 52 is held against axial movement by bearings 54 and 56 (see Fig. 4) and is secured to one end of a horizontally extending shaft 58 which extends forwardly through the front face of the base 20. The shaft 58 is supported adjacent the front face of the base 20 on a bracket 60 and carries a handwheel 62 fixed to its outer end.

The worm wheel 46 is secured to the upper end of a vertically extending screw 64, the lower end of which has a threaded engagement with an internally threaded nut 66 having an outwardly extending flange at its lower end, upon which the vertical slide 40 is supported by means of a bearing block 68 keyed to the slide as indicated at 70. It will now be appreciated that the vertical slide 40 may be adjusted upwardly or downwardly by rotation of the handwheel 62 in the appropriate direction.

The upper wall of the vertically movable slide 40 is formed to define a hollow cylindrical post 72 and an annular horizontally disposed surface 74 encircling the post 72. This annular surface 74 is engaged by a bearing ring 76 secured to the lower surface of a table 78 which defines a cylindrical bearing 80 in which the post 72 is journaled. A shaft 82 extends vertically through the hollow post 72 and has an annular flange 84 at its upper end which seats on an annular shoulder 86 defined by the table 78 at the upper end of the bearing 80. At its lower end the shaft 82 has a threaded stud portion 88 upon which is received a worm wheel 90 having a threaded central aperture adapted to threadedly engage the stud portion 88. A horizontally disposed worm 92 is rotatably supported in the side wall of the vertically movable slide 40 and is rotatable by a handle 94 disposed externally of the slide 40. Rotation of the handle 94 in one direction rotates the worm wheel 90 in a direction to draw the stud portion 88 and shaft 82 downwardly through the worm wheel 90, upward movement of the worm wheel 90 being prevented by a downwardly extending portion 96 of the post 72. It will be appreciated that this action results in the shaft 82 acting through the engagement of its flange 84 with the shoulder 86 to clamp the bearing ring 76 against the surface 74 on the vertical slide 40 and lock the table 78 against pivotal movement relative to the slide 40. Rotation of the handle 94 in the opposite direction releases this clamping action and permits the bearing plate 76 of the table 78 to rotate freely on the annular surface 74 of the slide 40.

A horizontally movable slide 98 is supported on the table 78 for reciprocatory movement relative thereto, and is held against tilting or lateral movement relative thereto as best illustrated in Fig. 5. The construction there illustrated is described in greater detail in the applicant's co-pending application Serial No. 125,706 filed November 5, 1949, now abandoned. Briefly, it comprises a bearing plate 100 secured to the upper surface of the table 78 by screws 102, and which is engaged along its opposite edges at its upper and lower sides by sets of antifriction elements 104, 106, 108, and 110. The upper antifriction elements 104 and 106 carry the weight of the slide 98 and the lower ones 108 and 110 co-operate with them to prevent tilting of the slide 98. One set of the upper antifriction elements, namely 104, are balls and co-operate with a V-shaped

raceway 112 in the plate 100 and a similar co-operating raceway 114 in a bar 116 secured within the slide 98 by screws 118. The remaining sets of antifriction elements 106, 108 and 110 are 5 cylindrical rollers which roll along raceways on the plate 100 and co-operating raceways on the members 120, 122 and 124 secured to the slide 98 by screws 126, 128 and 130 respectively. The individual balls and cylindrical rollers of the sets 10 104, 106, 108 and 110 are supported in spaced relation along the slide 98 by cages 129, 131, 132 and 133.

Movement of the slide 98 to the rear, or to the left as viewed in Fig. 3 is limited by the engagement of a stop 135 carried by the slide 98 and adjustable along a T-slot 137, best illustrated at 15 the right hand side of the slide 98 as viewed in Fig. 5, with a stop 139 fixed in the forward wall of the housing 166.

20 A rotary wheel support 138 is journaled on the forward end of the horizontal slide 98 for rotation with respect to the slide about a horizontal axis. The wheel support 138 has a rearwardly extending cylindrical projection 140 which is journaled within a cylindrical recess 142 formed in the forward end of the slide 98. The wheel support 138 is held against withdrawal from the recess 142 and in desired rotative adjustment relative to the slide 98 by a stud 144 having its inner end threaded into a tapped opening in a boss on the slide 98 and secured against rotation by a locking nut 146. The stud 144 extends axially through the cylindrical recess 142 and cylindrical projection 140 and projects outwardly 25 through the forward surface of the wheel support 138 where it receives a threaded cap nut 148. Upon tightening of the nut 148, the wheel support 138 is clamped against the outer annular surface of a dial ring 150 mounted on the forward end of the slide 98 and surrounding the recess 142.

30 The wheel support 138 carries an electric motor 152 having a shaft 154 operatively connected by pulley means (not shown) to a second shaft 156 35 disposed below and extending parallel to the shaft 154. The shaft 156 extends outwardly at one side of the wheel support 138 and carries a grinding wheel 158 secured thereto for rotation therewith.

35 Adjacent its forward end and at the right 40 hand side thereof, as viewed in Figure 1, the slide 98 carries a handle 160 mounted thereon for pivotal movement about a horizontal axis. In spaced relation below its pivotal mounting 162, and as 45 best illustrated in Fig. 12, the handle 160 has an aperture 164 for operatively connecting the handle 160 for effecting movement of the slide 98 as hereinafter described.

50 The table 78 carries a housing 166 having a horizontally disposed cylindrical socket 168, best illustrated in Fig. 5, which extends parallel to the aperture 164 in the downwardly extending end of the pivotally mounted handle 160. A thumb screw 170 is mounted on the housing 166 and has a shank portion extending tangentially into the socket 168 for a purpose hereinafter described. A second handle 172 (see Fig. 2) is pivotally connected at its upper end to a bracket 174 secured to and extending upwardly from the forward portion 55 of the table 78 at the opposite side of the slide 98 from the handle 160. The handle 172 is provided with an aperture (not shown) disposed in spaced relation below its upper end for operatively connecting the handle for effecting movement of the slide 98 relative to the table 78. The 60 slide 98 has a socket member 176 secured thereto 65

which has a horizontally disposed socket (not shown) similar to socket 168 formed in housing 166 and extending parallel to the aperture in the handle 172. The socket member 176 also has a thumb screw 178 having a shank portion extending tangentially into the socket thereof.

A link 180 is provided for selectively connecting the handle 160 to the housing 166 and the handle 172 to the socket member 176. The link 180 has a bifurcated fitting 182 at its forward end which carries a thumb screw 184 (see Fig. 12) having a shank portion 186 adapted to be inserted through an opening in one of the arms of the fitting 182 and be journaled in the apertures provided in the handles 160 and 172. At its inner end the screw 184 has a threaded stud portion adapted to threadedly engage in a tapped opening in the other arm of the bifurcated fitting 182. The link 180 also carries a cylinder 188 (see Fig. 5) adapted to be rotatably received in the socket 168 and the similar socket of the socket member 176. The cylinder 188 has an annular groove 190 disposed in spaced relation to its inner end and adapted to receive the shanks of the thumb screws 170 and 178 to permit rotation of the cylinder 188 relative to either the housing 166 or the socket member 176 while preventing axial movement of the cylinder 188. Adjacent its outer end, the cylinder 188 has a transversely extending opening 192 through which the link 180 extends. The cylinder 188 also carries a shoe 194 having a surface shaped to fit the link 180, and a thumb screw 196 mounted in the outer end of the cylinder 188 for forcing the shoe 194 against the link 180 to clamp the cylinder against movement relative to the link 180.

It will now be appreciated that the link 180 may be readily moved from the position illustrated in full lines in Fig. 4 to the position there illustrated in broken lines by removing the thumb screw 170 permitting the cylinder 188 to be withdrawn from the housing 166 and removing the thumb screw 184 from the fitting 182 to disconnect that fitting from the handle 160. The fitting 182 may then be connected to the handle 172 by means of the thumb screw 184 and the thumb screw 196 may be loosened to permit the cylinder 188 to be moved along the link 180 into alignment with the socket member 176 at which point the thumb screw 196 may be again tightened and the thumb screw 178 withdrawn to permit the cylinder 188 to be slipped into the socket of the socket member 176 after which the thumb screw 178 may be replaced to prevent withdrawal of the cylinder 188 from the socket member 176.

The slide 98 also carries a second stop 200 adjustable along the T slot 137 and disposed rearwardly of the stop 135, or to the right thereof as viewed in Figure 11. The stop 200 is secured in the position illustrated in broken lines adjacent the rear of the slide 98 when the link 180 is in the position illustrated in broken lines in Fig. 4 to render the handle 172 operative as when the machine is set up for sharpening surface broaches. When the machine is set up for sharpening round broaches and the handle 160 is rendered operative by the link 180, the stop 200 is fixed in approximately the position illustrated in full lines in Figures 4 and 11, forward movement of the slide 98 in response to the operation of the lever 160 is limited by the engagement of the stop 200 with an adjustable stop 202 mounted in the housing 166 secured to the table 78.

Referring particularly to Figs. 7 and 8, the stop 202 is cylindrical in shape and is mounted in a

rearwardly extending cylindrical portion 204 of the housing 166 for axial movement between the retracted position there illustrated in full lines and the extended position illustrated in broken lines in Fig. 7. The stop 202 is held against rotation relative to the cylindrical housing portion 204 by a key 206. The extended and retracted positions of the stop 202 are determined by a set screw 208 projecting into a slot 208 formed in the side of the stop 202 and engaging the stop 202 at the opposite ends of the slot 208 when the stop 202 is at its extended and retracted positions. Axial movement of the stop 202 is effected by means of a stud 210 mounted in the housing 166 for rotation about a horizontal axis and held against axial movement by bearings 212 and 214. A rearwardly extending end portion 216 of the stud 210 has a threaded engagement with the stop 202. Rotation of the stud 210 is effected by means of a spiral gear 218 secured on the forward end of the stud 210 in driving engagement therewith. The spiral gear 218 is drivingly engaged by a co-operating spiral gear 220 which is secured on the upper end of and driven by a vertically disposed shaft 222 which is rotatably supported in the housing 166 and secured against axial movement by bearings 224 and 226. The shaft 222 is fixed to one end of a flexible cable 228 by means of a set screw 230, the other end of the flexible cable 228 being secured to a second vertically disposed shaft 232 which is rotatably mounted and held against axial movement by bearings 236 and 238 mounted in a housing 234 secured to the rear of the base 20. A bevel gear 240 is fixed on the upper end of the shaft 232 for rotation therewith and is drivingly engaged by a second bevel gear 242 fixed on the rear end of a horizontally extending shaft 244 which extends transversely through the base 20, the rear end projecting into the housing 234 and the forward end projecting into a sleeve 246 to which the shaft 244 is keyed as at 248. At its forward end the sleeve 246 projects into a gear housing 250 wherein it carries a gear 252 keyed thereto as at 254. The sleeve 246 is rotatably supported in bearings 256 and 258. The gear housing 250 is secured to the base 20 by a plurality of screws 260, see Fig. 1, and rotatably supports an intermediate gear 262 meshing with the gear 252, and an upper gear 264 meshing with the intermediate gear 262. A pin 266 extends radially through the upper gear 264 to fix the same on a shaft 268 extending horizontally through the cover plate 270 on the front face of the gear housing 250 and carries a handwheel 272 fixed on its outer end by means of a transversely extending pin 278. The handwheel 272 carries an annular dial 276 secured to the hub portion of the handwheel by a set screw 274 seating in an annular groove 280.

It will now be appreciated that rotation of the handwheel 272 is effective through the shaft 268, the gears 264, 262, and 252, the sleeve 246, the shaft 244, the bevel gears 242 and 240, the shaft 232, the flexible shaft 228, the spiral gears 220 and 218, and the stud 210, to adjust the stop cylinder 202 along its horizontal axis.

An example of one manner of using the above described adjustable stop mechanism in the sharpening of round broaches is as follows. The 70 broach is mounted in the centers as shown in Figure 1. The cap nut 148 is then loosened to permit rotation of the wheel support 138 to a position in which the axis of the grinding wheel spindle 156 lies in a horizontal plane. The handwheel 62 is then rotated to adjust the vertical

slide 40 to the position in which the grinding wheel 158 is on the same horizontal level as the axis of the broach. The handle 94 is then turned to release the table 78 which is rotated until the plane of the grinding wheel corresponds to the angle made by the face of the broach teeth and it is then clamped in that position by manipulation of the handle 94.

The sharpening operation may then be carried out in differing ways, one of which may include starting at the end of the broach where the root diameter is a maximum and adjusting the stop 202 by means of the handwheel 272 so that when the grinding wheel 158 is fed forwardly to the limit permitted by the engagement of the stop 200 with the adjustable stop 202 the infeeding of the grinding wheel is stopped at the desired point. It will now be appreciated that in grinding successive teeth of the broach, the root diameters of which are progressively smaller, the grinding wheel may be fed inwardly until the stop 200 engages the stop 202 without fear of excessive infeeding of the grinding wheel and that the additional infeed required in each instance because of the reduction in the root diameter may be readily permitted by a slight adjustment of the handwheel 272. It will now be appreciated that the broach sharpening machine is arranged so that during such broach sharpening operation the operator may conveniently feed the grinding wheel transversely of the broach by means of the handle 160 with his left hand and may adjust the position of the work slide 22 along the base 28 by means of the handle 23 with his right hand, which right hand may also alternately be used for adjustment of the stop 202 by means of the handwheel 272.

The machine is set up for the sharpening of surface broaches by moving the connecting link 180 to the position illustrated in full lines in Fig. 2 and in broken lines in Fig. 4, in which position it renders the handle 172 effective for feeding the slide transversely of the broach which is supported as illustrated in Fig. 2. The stop 200 is also moved along the T slot 137 from the position illustrated in full lines in Figs. 4 and 11 to the position there illustrated in broken lines. The handle 94 is turned to release the table 78 which is then rotated to a position in which the path of movement of the horizontal slide is parallel to the broach teeth, and the table 78 is then clamped in this position by turning the handle 94. The nut 148 is then loosened and the wheel support head 138 is rotated to a position such as that illustrated in Fig. 2 in which the plane of the grinding wheel 158 lies in the plane of the front faces of the broach teeth. The handwheel 62 is then turned to adjust the vertical slide 40 to the position in which the grinding wheel 158 is at the proper height to grind to the root of the teeth.

While only one embodiment of the invention has been illustrated and described in detail, it will be readily appreciated by those skilled in the art that numerous modifications and changes may be made without departing from the spirit of the invention.

What is claimed is:

1. In a machine for sharpening broaches, a base, a horizontally movable slide mounted on said base, means on said slide for supporting and rotating a broach to be sharpened, means including a manually operable element disposed at one side of said base for effecting horizontal movement of said slide, a table member supported on said base remote from said one side thereof and

rotatable about a vertical axis, a horizontally movable slide member mounted on said table member, a grinding wheel mounted on said slide member, means for moving said slide member horizontally, a stop secured to said slide member, adjustable stop means mounted on said table member remote from said one side of said base and including a stop element adapted to abut said stop on said slide member to limit horizontal movement of said slide member in one direction, and remote control means for adjusting said adjustable stop means and including a manually operable element mounted on one side of said base adjacent said first named element, means interconnecting said manually operable element and the said stop element of said adjustable stop means whereby an operator may readily adjust said adjustable stop means from his normal position at said one side of said base.

2. In a machine for sharpening broaches, a base, a slide mounted on said base for horizontal movement relative thereto, means on said slide for supporting a broach to be sharpened in parallel relation to the line of movement of said slide and rotating the broach, means including a handwheel at one side of said base for effecting said horizontal movement of said slide, a table member supported on said base remote from said one side thereof, a slide member mounted on said table member, a grinding wheel, means mounting said grinding wheel on said slide member for rotation about a substantially horizontal axis, means for rotating said grinding wheel, said table member being rotatable about a vertical axis to align the working surface of the grinding wheel with the front faces of the broach teeth, said slide member being movable horizontally in one direction relative to said table member to move said grinding wheel working surface into the space between adjacent broach teeth, a stop secured to one of said members, adjustable stop means mounted on the other of said members remote from said one side of said base and including a stop element adapted to abut said stop to limit movement of said slide member relative to said table member in said one direction, remote control means including a second handwheel mounted on one side of said base adjacent said first named handwheel and operable for effecting adjustments of the stop element of said adjustable stop means, means including a flexible connector interconnecting said second handwheel and the said stop element of said adjustable stop means, whereby an operator may readily adjust said adjustable stop means to compensate for variations in the root diameter of the broach from his normal position at said one side of said base, and means adapted to be operated by said operator from said position for moving said slide member in said one direction.

BENEDICT WELTE.
